SUPERHETERODYNE RECEIVER

Klaas Posthumus and Theodorus Josephus Weyers, Eindhoven, Netherlands, assignors to Radio Corporation of America, a corporation of Delaware

Application December 18, 1933, Serial No. 702,912
In Germany January 2, 1933

1 Claim. (Cl. 250—20)

The present invention relates to oscillator circuits for superheterodyne receivers, and particularly to oscillator circuits for superheterodyne receivers for obtaining a constant intermediate frequency.

In the usual superheterodyne receivers use is mostly made of a local oscillator circuit consisting of two parallel branches comprising a series and parallel connection of condensers and a self-inductance respectively, as is shown in Fig. 1. The tuning device of the local oscillator circuit is preferably mechanically coupled with the tuning device of the circuits tuned to the signal to be received in order to obtain the simplest possible adjustment of the receiving set. Such tuning has the drawback that the difference between the resonance frequencies of the oscillator circuit and of the circuit tuned to the signal to be received is for all the frequencies not equal to the intermediate frequency. Figure 2 shows the difference of these resonance frequencies for the frequency range to be received, said difference being designated by the difference frequency V^1 . V_1 is the lowest, V_2 the highest frequency to be received, and V_m is the intermediate frequency to which the intermediate frequency circuits are tuned. The elements of the circuits are preferably so taken that for V_3 and for V_4 the differences between V^1 and V_m are equal in absolute value. If $V_2=3V_1$ this difference is for V_3 , and for V_4 about 1.5% of V_m . For receiving, for example, the frequency V_3 , the tuning members are adjusted in such manner that the oscillator frequency amounts to V_3+V_m .

The tuning is substantially determined by the most selective element of the receiving apparatus, in the present case by the intermediate frequency circuits. In this case the frequency V_3 to be received differs by

$$40 \quad \left(\frac{1.5}{100} = V_m \right)$$

from the resonance frequency of the high-frequency circuits as is shown in Figure 3. The curve a represents the resonance curve of the high frequency circuits where the resonance frequency is V_r . V_3 is the frequency to be received, and V_3+V_m is the oscillator frequency, the difference between V_3+V_m and V_r being V^1 . Too large a difference between V^1 and V_m results in a reduction of the amplification and in distortion. If the maximum difference of 1.5 KC/sec. is allowed, the maximum intermediate frequency which may be employed amounts to 100 KC/sec.

55 A higher intermediate frequency affords, how-

ever, the advantage that with an equal number of tuned circuits the so-called reflected-image frequency ("spiegelbildfrequenz") and other frequencies which may give rise to a disturbing whistling noise are better suppressed, or that with the same effective action of the high-frequency part the number of circuits may be reduced.

The object of the present invention is to form the local oscillator circuit in such manner that in all the positions of the tuning members the difference between the resonance frequencies of the circuits tuned to the frequency to be received and of the oscillator circuit is as much as possible equal to the intermediate frequency, and more particularly that with the same intermediate frequency the maximum value of this difference is smaller than in the usual circuit-arrangement, and that consequently with a constant maximum difference between V^1 and V_m the intermediate frequency V_m may be higher.

In the drawings:—

Fig. 1 is a circuit arrangement of a conventional superheterodyne receiver showing the prior art construction of the local oscillator.

Figs. 2 and 3 show characteristics of the receiver of Fig. 1.

Fig. 4 shows one form of the invention applied to the local oscillator network of the receiver in Fig. 1.

Fig. 5 illustrates a characteristic of the circuit of Fig. 4.

Fig. 6 shows another modification, and Fig. 7 illustrates the characteristic thereof.

Fig. 8 shows a modification of the arrangement of Fig. 6, Fig. 7 illustrating its characteristic.

Fig. 9 shows another modification, Fig. 10 illustrating its characteristic.

Figs. 11, 12 and 13 show further modifications.

Fig. 14 shows still another modification, Fig. 15 depicting its characteristic.

In the present invention there is added to the circuit-arrangement according to Figure 1 one or more elements of which at least one is a resistance. The condenser C_2 in Figure 1 operates so that for frequencies lower than V_3 the difference frequency increases when the frequency decreases. The receiver circuit in Fig. 1 is conventional, and the dotted line 1 represents the tuning control means. If care is taken to ensure that C_2 increases with decreasing frequency, the difference frequency increases less rapidly or even decreases when the frequency decreases. This could be obtained by making the condenser C_2 variable, but the result aimed at may be obtained in a

simpler manner by connecting, as shown in Fig. 4, a resistance R_1 , preferably of determined value, in parallel with condenser C_2 .

The impedance of this parallel connection of 5 the condenser C_2 and the resistance R_1 amounts to

$$K = \left(\frac{R_1}{1 + R_1^2 \omega^2 C_2^2} \right) - j \left(\frac{R_1^2 \omega C_2}{1 + R_1^2 \omega^2 C_2^2} \right)$$

10 When assuming this impedance to be equal to

$$R^1 + \frac{1}{j\omega C^1}$$

we have

$$15 C^1 = C_2 \left(1 + \frac{1}{R_1^2 \omega^2 C_2^2} \right)$$

This equation states in mathematical language 20 that the effective capacity C^1 is equal to the actual condenser capacity C_2 , plus C_2 times a fractional (or percentage) increase, which fraction, for convenience, shall be referred to as r . In this equation,

$$\frac{1}{R_1^2 \omega^2 C_2^2}$$

25 is the fractional increase. Knowing the fractional increase desired at the low frequency end of the band of frequencies over the high frequency end in order to maintain "tracking", it remains only to find what value R_1 will make the expression

$$\frac{1}{R_1^2 \omega^2 C_2^2}$$

(the fractional increase) have the desired value. 30 Since

$$\frac{1}{R_1^2 \omega^2 C_2^2}$$

and r both represent the same thing, we have

$$40 R_1 = \frac{1}{\omega C_2 \sqrt{r}}$$

The effect of the resistance R_1 is consequently 45 an increase of the virtual resistance of the circuit (which with an oscillator circuit is no preponderant drawback), and an increase of the virtual capacity in the case of a decreasing frequency.

The result aimed at may consequently be obtained by giving the resistance R_1 such a value 50 that for the frequency V_1 the value $R_1^2 \omega^2 C_2^2$ is no longer very large relatively to 1 (e. g. 4). Figure 5 shows the difference frequency as a function of the frequency to be received with this circuit-arrangement. The largest difference between the difference frequency and the intermediate frequency is in this case about 0.3% of the intermediate frequency.

In a similar manner it may be explained that 60 with a circuit-arrangement as shown in Figure 6 in which a resistance R_2 is connected in series with a condenser C_3 , the difference frequency plotted as a function of the frequency to be received has the shape shown in Figure 7.

Figure 8 represents a modified form of execution 65 of the circuit-arrangement according to Figure 6, in which the branch $R_2 C_3$ is connected in parallel with L_1 . For this circuit-arrangement the difference frequency is also represented by Figure 7.

70 Another circuit-arrangement according to the invention is shown in Figure 9. In parallel with

the circuit according to Figure 1 is connected a branch consisting of the series connection of a resistance R_3 and a circuit formed by a self inductance L_2 , a resistance R_4 and a capacity C_4 . This circuit $L_2 C_4$ is tuned to the frequency V_5 (Figure 5 2). For this frequency this circuit has a real impedance. The natural frequency of the original circuit consisting of L_1 , C_1 , C_2 and C_3 is not appreciably influenced by the branch added in accordance with the invention. For the frequencies V_1 and V_2 the impedance of the circuit formed by L_2 and C_4 is small. The impedance of the circuit formed by L_2 and C_4 is small. The impedance of the branch R_3 , L_2 , C_4 also becomes almost real, and hardly acts on the oscillator frequency. For frequencies slightly lower than V_5 the impedance of the circuit $L_2 C_4$ is inductive and increases the oscillator frequency. For frequencies slightly higher than V_5 the impedance of the circuit $L_2 C_4$ is a capacitative one and consequently decreases the oscillator frequency.

For this circuit arrangement Figure 10 shows the difference frequency as a function of the frequency to be received. In order to ensure that in the neighborhood of V_5 the influence of the 25 circuit $L_2 C_4$ should not become too large, the damping of this circuit must be rather large. This may be obtained by adding a resistance R_4 or by winding the coil L_2 of resistance wire.

The circuit arrangements according to Figures 30 11, 12 and 13 dually correspond to those of the Figures 4, 6, 9 respectively. For two dual circuit arrangements the difference frequency is equal.

Some of the circuit arrangements shown may also be combined. Figure 14 represents a combination of the circuit arrangements of Figures 4, 35 6 and 9. Figure 15 shows the variation of the difference frequency in this case.

The above-described circuit arrangements 40 may still be extended by adding to the oscillator circuit various elements among which there are also resistances. For practice, however, the circuit-arrangements described give as a rule a sufficiently constant different frequency.

While we have indicated and described several 45 systems for carrying our invention into effect, it will be apparent to one skilled in the art that our invention is by no means limited to the particular organizations shown and described, but that many modifications may be made without departing 50 from the scope of our invention, as set forth in the appended claim.

What is claimed is:—

In combination, in a heterodyne receiver, a first detector having a means tunable over a 55 frequency range, and a local oscillator coupled to said first detector and comprising a tunable frequency control circuit, said frequency control circuit comprising an inductance and two condensers in series with each other and in parallel with 60 said inductance, one of said condensers being variable for varying the tuning of said frequency control circuit, and a resistance in parallel with the other said condenser, the value of said resistance measured in ohms being equal to a number 65 of the order of twice the reactance of the other condenser at the lower end of the frequency range, and means for uni-controlling said tunable means and said variable condenser.

KLAAS POSTHUMUS.
